INVENTOR

J. F. Hunter.

UNITED STATES PATENT OFFICE.

JACOB F. HUNTER, OF NEW YORK, N. Y., ASSIGNOR TO HIMSELF, H. A. HUNTER, AND P. P. KELLER, OF SAME PLACE.

IMPROVEMENT IN HOT-WATER APPARATUS.

Specification forming part of Letters Patent No. 27,670, dated March 27, 1860.

To all whom it may concern:

Be it known that I, JACOB F. HUNTER, of New York, in the county and State of New York, have invented a new and Improved Hot-Water Apparatus for Heating Buildings; and I do hereby declare that the following is a full, clear, and exact description thereof, reference being had to the accompanying drawings, forming a part of this specification, in which—

Figure 1 represents a vertical diametrical section taken through my improved apparatus, exhibiting clearly the arrangement of the hot-water pipes, &c. Fig. 2 is an exterior view of the apparatus.

Similar letters indicate corresponding parts in both figures.

A represents a water back or boiler of any description, which is mounted upon masonry B B, forming the ash-pit C.

D is the grate, and E is the fire-place. This water-back A consists of a hollow cylindrical vessel surrounding the bed of coals and extending up a sufficient distance to form a guard for the body of heated coals to confine them within the fire-place.

F G are two coils of metal tubing coiled spirally and arranged one within the other, which extend up to any desirable height over the fire-chamber and connect with a main pipe J, to which the pipes communicating with the registers in the building are attached, as clearly shown by the drawings, Fig. 1, and from the register a return-pipe is connected, which communicates with the water-back or fire-pot A. In this manner a con-

tinuous circulation of the hot water is kept up in the apparatus and throughout the building. The water in its highly-heated state passing up from the fire-back A and through the spiral coils of pipes F G is rapidly heated on account of the great surface exposed to the action of the fire and heated air and a rapid circulation of hot water through the registers or radiating-surfaces, of any shape or description, which may be disposed throughout the building.

The entire boiling apparatus is inclosed within a metal casing K, from which the products of combustion are conducted off through an escape-flue L to the chimney.

The cold-water supply and appurtenances employed about my apparatus are similar to those of the same class of invention now in common use, and therefore not necessary to represent or describe.

I do not desire to claim as my invention the use of coils of pipes for hot-water apparatuses irrespective of arrangement; but

What I claim as my invention, and desire to secure by Letters Patent, is—

The combination of the coils F G with the main pipe J, fire-back A, return-pipe J', and casing K, when the said coils are both connected with the main pipe J and back A and otherwise constructed, as herein shown and described, for the purpose set forth.

J. F. HUNTER.
